UNITED STATES PATENT OFFICE.

HARLAN J. MAYNARD, OF NEWTON HIGHLANDS, MASSACHUSETTS, ASSIGNOR TO
THERMOLAC MANUFACTURING COMPANY, OF BOSTON, MASSACHUSETTS, A COR-
PORATION OF MASSACHUSETTS.

NIPPLE FOR NURSING-BOTTLES.

1,060,777.

Specification of Letters Patent.

Patented May 6, 1913.

Application filed May 6, 1911. Serial No. 625,553.

To all whom it may concern:

Be it known that I, HARLAN J. MAYNARD, a citizen of the United States, and resident of Newton Highlands, in the county of Middlesex and State of Massachusetts, have invented certain new and useful Improvements in Nipples for Nursing-Bottles, of which the following is a specification.

In feeding children it is found that one of the greatest difficulties is to control the rapidity with which the food is taken and that too rapid feeding is one of the chief causes of infantile disorders.

The object of the present invention is to produce a nipple for a nursing or feeding bottle which can be readily manipulated so as to control the rapidity with which the child extracts the fluid from the bottle.

The invention will be described in connection with the accompanying drawing, in which:

Figure 1 is a perspective view of a nipple for a nursing bottle embodying the present invention; and Fig. 2 is a longitudinal cross section through the discharge orifice.

The invention is applicable to any form of nipple, whether rigid or flexible, and I have illustrated it in connection with one of the commonly used forms.

In nipples as ordinarily constructed there are one or more openings at or near the outer extremity and it is not practicable to control the flow of the fluid. In some instances the openings have been purposely made so as to permit of a free flow of the liquid food. According to the present invention I provide the nipple A with a small opening or perforation *a* at one side of the forward part of the nipple and extending through from the interior to the outer surface thereof. With a nipple so constructed the fluid may be extracted with sufficient rapidity while the axis of the opening *a* is

horizontal. By turning the bottle and nipple so as to bring the opening *a* into contact with either the tongue, or the roof of the child's mouth, the discharge through the opening will be restricted, the tongue or the roof of the mouth acting as a valve to close or partially close the opening. The feeding may thereby be controlled or regulated as desired. As an aid in regulating the feeding I preferably provide an index point or marker *b* on the base of the nipple and in the same axial plane as the orifice *a* so that when the latter is hidden in the child's mouth its position may be accurately determined.

It will be evident that my invention may be applied to nipples of various contours, whether rigid or flexible. It will also be evident that two or more perforations might be substituted for the single opening *a*, provided such perforations are so grouped as to be the equivalent of the single opening. That is, so grouped that the tongue, or the roof of the mouth may be used as a valve to close them. In the preferred form of my invention however the nipple is provided with a single lateral perforation or opening as shown in the drawing.

Having described my invention what I claim and desire to secure by Letters Patent is:

A nipple for nursing or feeding bottles having a perforation in and through its side wall and having a portion to fit over the neck of a bottle, the said nipple being otherwise imperforate, for the purpose set forth.

In testimony whereof I affix my signature in presence of two witnesses.

HARLAN J. MAYNARD.
